HUMIDIFIER

Richard C. Wittman, Emporium, Pa.

Application July 30, 1941, Serial No. 404,665

2 Claims. (Cl. 261—103)

This invention relates to humidifiers, and more particularly to humidifiers to condition the air in homes and offices for human consumption.

It is a well-known fact that in our present civilization homes and offices are many times kept at high temperatures during cold weather. The heat expands the fresh air which seeps into the rooms and through such expansion reduces or evaporates the moisture normally present in the air, with the result that it becomes too dry and is detrimental to health.

An object of this invention is to provide a humidifier which may be readily adapted to existing heating systems and which will provide an adequate amount of moisture in the air.

A further object is to provide a unit of the type described which will be simple in construction, automatic and economical in operation, and which will require very little care or supervision.

A still further object is to provide a humidifier which will not occupy a great amount of space and which may be placed in any convenient location.

Other objects and advantages of my invention will become apparent as the description proceeds.

In the accompanying drawings—

Fig. 1 is a side elevation in cross section of a humidifier embodying my invention;

Fig. 2 is an end view thereof, taken on the line 2—2 of Fig. 1;

Fig. 3 is a cross sectional view taken on the line 3—3 of Fig. 1;

Fig. 4 is a detailed view of the tubes used to distribute the water;

Fig. 5 is a view showing the manner in which my invention may be tapped into the ordinary hot air furnace;

Fig. 6 is a view showing the manner in which the device may be used with the conventional steam or hot water heating system.

I provide an outer casing 10 which may be provided with doors 11 and 12 hinged thereto at 13. The casing 10 is provided with an intake pipe 14 and outlet pipes 15, 16 and 17. Obviously, there may be as many intake and outlet pipes as is necessary for the particular use to which the unit is to be put.

Mounted in the upper portion of the unit on the angle iron 20 by means of the supporting rod 21 is a water pan 22 carrying non-corrosive tubes 23. As shown in Fig. 4, the tubes 23 are provided with openings 24 and may have at their ends clean-out plugs 25. Between the angle 20 and the pan 22 are screw plugs 26 so that the position of the pan may be adjusted by turning the

plugs 26 or by manipulating the bolt 27 on the supporting member 21.

Mounted below the pan 22 are the rods 30 which support fabric sheets 31. These sheets may be made of any suitable absorbent fabric but best results are secured by using a fabric having an uneven surface. Below the ends 32 of the sheets 31 are mounted additional supports 33 and sheets 34 are folded over the supports.

At the bottom of the casing 10 is a water pan 35 which is adapted to collect any water flowing from the sheet 31. The ends 36 of the sheet 34 extend into the bottom of the pan and take up the water from the pan. A faucet or tap 37 is provided. This faucet 37 will serve a double function. It may of course be used to lower the level of the water in the pan 35 or it may be adjusted to allow a continual stream of water to flow therefrom. Under certain conditions, such as in public buildings, it may be desirable to maintain a high degree of saturation of the sheet 31. In such an instance, the faucet 37 may be adjusted to continually drip or allow a small stream to flow therethrough so that fresh water will be continually supplied to the sheets 31 and of course to the sheets 34.

Water is supplied to the pan 22 through the pipe 40 which leads to a straining assembly 41, through the pipe 42 to the valve 43. The valve 43 is controlled by the rod 45 which is slidably mounted in supports 46 and which at its lower end has a float 47. It will be seen that when water is high in the pan 35, the float 47 and rod 45 will be raised to turn off the valve 43. However, as the water is used in the pan 35, the float will be lowered and the valve 43 opened to allow additional water into the pan 22.

Mounted in the casing 10 adjacent the intake pipe 14 is a deflecting shield 50, and mounted in the intake pipe is a fan 51. As the air is drawn through the intake pipe the shield 50 deflects it down around the sheets 34 so that the air is humidified even before it passes through and around the sheets 31.

Fig. 5 shows the manner in which my device may be adapted to the hot air ducts of the average furnace. The pipe 14 would lead from the furnace and the air would be passed through the humidifier out through the pipes 15 and 17 to the registers 53 and 54.

Where the system is used with a steam or hot water furnace, ducts 55 and 56 may be placed below the average radiator and the air drawn down through the intake pipes 14 and 57 by means of the fans 51 and 58 into and through the

humidifier and out through the pipes 15 and 17 to the ducts 59 and 60.

It will be seen that with my humidifier a constant supply of moisture is furnished to replace the moisture dissipated by heat and expanding air. It will also be seen that the amount of water in the humidifier will be automatically controlled at all times, and that the water which flows over and off of the sheet 31 is used by the sheet 34 so that the humidifier will be most economical to operate.

It will be further seen that the humidifier is supplied with two adjustable means of water disposal. The first is adjustable by the area and character of the absorbent members 34 that are exposed to the air currents for evaporating the surplus and by the effectiveness with which the air currents can be brought into contact with them. The other is provided by the adjustable faucet or tap 37. It will be appreciated that, in addition to the moisture held by the absorbent members 31 and 34, the air currents will be further moistened by passing over the water in the pan 35.

While I have shown fans 51 and 53 located at the air inlet of the humidifier, these fans may

be placed at any convenient point in the system where they will function to draw the air from the rooms through the humidifier.

I claim:

5. A humidifier comprising a casing, air inlet means for the casing adjacent the bottom thereof, air outlet means for the casing adjacent the top thereof, absorbent sheets positioned within the casing between said inlet and outlet means, means for distributing liquid to said sheets, a vessel within the casing on the bottom thereof to catch excess liquid, a second group of absorbent sheets within said casing adjacent said inlet means and depending into said vessel, a float in said vessel responsive to the rise and fall of liquid in said vessel, and valve means cooperating with said float to control the flow of liquid to said distributing means.
10. 2. A humidifier as set forth in claim 1, wherein said liquid distributing means consists of a pan and perforated spaced pipes extending laterally from said pan to be fed by the latter, and said valve means when open, because liquid in said vessel has fallen to a predetermined level, discharges liquid into said pan.

RICHARD C. WITTMAN.
